CLAIM

The ornamental design for a hanging chair stand, as shown and described.

DESCRIPTION

FIG. 1 is a front right side perspective view of a hanging chair stand showing my new design, a hanging chair being shown in broken lines for illustrative purposes to show the environment of use of the stand, the hanging chair shown in broken lines forming no part of the claimed design;

FIG. 2 is a front elevational view thereof;

FIG. 3 is a top plan view thereof;

FIG. 4 is a right side view thereof;

FIG. 5 is a rear elevational view thereof;

FIG. 6 is a bottom plan view thereof; and,

FIG. 7 is a left side view thereof.
